RAZOR SHARPENING DEVICE

Bo Gabriel Montgomery, Djursholm, Sweden, assignor to Aktiebolaget Oryg, Gottenborg, Sweden, a joint-stock company

Application August 4, 1930, Serial No. 472,985, and in Sweden July 9, 1930

2 Claims. (Cl. 51—65)

The present invention relates to safety razors and particularly to a combination container and stropping device.

More particularly the invention relates to a combined case and stropping device for a safety razor of the type having a frame, a pivot, a blade holder pivoted to the frame and a blade carried in the blade holder, the container being provided with a cover member reciprocable thereon and provided with stropping means on its inner side adapted to be contacted by the blade of the razor when the razor is in its normal position in the container.

The principal object of the invention is to provide a combined case and stropping device for a razor of the aforementioned type which will be simple and compact in construction and will operate efficiently as a stropping device.

Other objects of the invention will appear from the following description taken in connection with the appended drawing wherein:

Fig. 1 shows a longitudinal section of a device adapted for the sharpening and keeping of a safety razor, a razor being shown in its normal position within the box. Fig. 2 shows this box as viewed from above with the lid removed. Fig. 3 is a cross-section on line 3—3 in Fig. 1, and Fig. 4 is a similar cross-section of the box according to a somewhat modified embodiment.

In Figs. 1-3 is shown a casing or box 21 made from sheet metal said box 21 being preferably of a rectangular basic shape and provided with plane upright sides adapted to be closed by means of a lid 22 slideable along the top of the box. To this end the box is furnished with runners 23 at the upper edges of its longitudinal external sides the lid being provided with corresponding tracks 24 in which the runners slide. If the cover is made from sheet metal bent to U-shape as shown in the drawing the said tracks 24 may be formed either by being bent at right angles to the side walls of the box or recurved over the runners 23 in such a manner that two longitudinal sliding edges 25 of the latter are caused to bear against the lower side of the runners. Between the edges thus formed and the bottom of the lid is introduced a plate 27 provided with a stropping member 26 said plate 27 being actuated by two transversal leaf springs 28 secured to the plate and bearing against the bottom of the lid the plate with the stropping member being thus resiliently arranged in a direction towards the blade holder. The runners of the box slide between the edges 25 and the bottom of the plate

27. The position of the plate in the lid is preferably fixed with its one end edge against a projection 29 formed on the back of the lid by a recurvature of the plate which projection also constitutes an abutment against the one short side of the box limiting the movement of the lid in one direction the position of the plate in the lid being also fixed by the plate forming an abutment with one of the side edges of the leaf springs against bosses 30 provided on the lower side of the lid.

To retain the safety razor in the box 21 the one short side of the latter has a catch 31 attached to it adapted to grip the sleeve 19 on the end of the handle. Further a U-shaped holder 32 is fixed to the bottom of the box the upwardly directed legs of said holder being provided with recesses 33 adapted to receive the fork portion 34 of the razor. The razor is placed in the box by inserting the handle end into the catch 31 whereupon the fork portion 34 is placed in the recesses 33. The safety razor is of a known type having a handle 1 which terminates in the bifurcated arms 2, 3 that pivotally support the blade holder 5 in which a blade 6 is clamped. Meshing gears 7, 8 on the blade holder and a friction roller 10 provide an automatic reversing of the blade during the sharpening operation.

The friction roller 10 is kept pressed against the stropping member 26 by the springs 28 so that the said roller is turned by friction when the lid 22 is slid to and fro along the top of the box 21 whereby the holder 5 with the razor blade 6 will adjust itself through the gear wheels 7 and 8 in such a manner that the edges of the blade are turned forward in the direction in which the stropping member 26 slides. The power with which the edge is pressed against the stropping member is dependent upon the nature of the friction surfaces of the roller and the stropping member as well as on the tension of the springs 28, on the ratio of gear of the gear wheels and on the position and diameter of the roller. By suitably selecting the value of the tensions of the springs 28 it is possible to perform the stropping of the edges at such a pressure that the edges of the razor blade always obtain a good and uniform sharpness.

The holder 32 arranged to retain the safety razor in the box may as shown in Fig. 4 be replaced by a spring clamp 35 adapted to embrace partly the upper portion of the handle 1 the said clamp being preferably carried by a spring 36 attached to the bottom of the box as illustrated

so that the safety razor is pressed upwardly in a direction toward the stropping member 26. In this case no springs are required between the cover and the plate 27 carrying the stropping member. Alternatively the latter may be fixed 5 directly on the bottom of the lid.

If desired, the device may also be constructed so that the blade holder 5 with the blade 6 is caused to perform a transversal movement relatively to the stropping member simultaneously 10 with the sliding motion of the latter. To this end the blade holder 5 with its shaft 4 may be axially movable between the shanks 2 and 3 and the said shaft 4 may be arranged to project through suitable openings in the longitudinal 15 side walls of the box and to bear against the recurved borders 25 of the cover 22 the said borders being here made slanting in relation to the direction in which the lid moves so that the shaft 4 with the holder 5 and the blade 6 20 will slide sideways when the lid is moved to and fro.

The details of the device may be subjected to alterations with respect to the construction thereof within the scope of the invention. Thus 25 the box or casing may be replaced by a frame or the like the cover carrying the stropping member then consisting of a slide suitably formed for its purpose. Further the toothed gearing 7, 8 arranged to rotate the blade holder 30 may be replaced by a suitable friction wheel gearing. The guiding of the plate in the slide or lid as well as the spring arrangement may be devised in any suitable manner. Thus for instance the springs may be formed directly out of the 35 material of the cover 22 or the plate 27 provided these parts consist of a thin elastic mate-

rial. To facilitate the stropping of razor blades or knives devised in some other way the blade holder 5 may be arranged to be exchangeable. Moreover, the locking member for the razor blade may take the form of slides provided with 80 slots or the like and displaceable in a direction at right angles or substantially at right angles to the longitudinal direction of the handle said slides being arranged on the fork shanks or the parts connected therewith.

What I claim is:—

1. A blade sharpening device for razors of the type having a pivoted blade holder carrying a blade and a friction roller geared to the blade holder, comprising a box, a slidable lid for completely closing the box, blade sharpening means on the inside of the lid, razor-receiving means within said box for supporting a complete razor to position the friction roller thereof adjacent the said sharpening means, and spring actuated means in said box for urging said friction roller and said sharpening means into mutual contact. 95

2. A blade sharpening device for razors of the type having a pivoted blade holder carrying a blade and a friction roller geared to the blade holder, comprising a box, a slidable lid for completely closing the box, blade sharpening means on the inside of the lid, razor-receiving means within said box for supporting a complete razor to position the friction roller thereof 100 adjacent the said sharpening means, and means in said box for urging said friction roller and said sharpening means into mutual contact, said urging means including a spring disposed between the inside of said lid and said sharpening 105 means. 110
